CLAIM

The ornamental design for a disposable syringe, as shown and described.

DESCRIPTION

FIG. 1 is a left side perspective view of a disposable syringe seen slightly from below, showing our new design; FIG. 2 is a right side perspective view thereof, seen slightly from above;

FIG. 3 is a right side elevational view thereof;

FIG. 4 is a left side elevational view thereof;

FIG. 5 is a side elevational view thereof, rotated ninety degrees from that shown in FIG. 3;

FIG. 6 is a side elevational view thereof, rotated ninety degrees from that shown in FIG. 4;

FIG. 7 is a bottom plan view thereof;

FIG. 8 is a top plan view thereof; and,

FIG. 9 is a left side perspective view thereof, seen slightly from above, with the piston rod protruding in its full length.
